UNITED STATES PATENT OFFICE.

COMMODORE R. MILLER, OF WOODLAWN BOROUGH, PENNSYLVANIA, ASSIGNOR, BY MESNE ASSIGNMENTS, TO SUPERIOR GAS IMPROVEMENT COMPANY, OF PITTSBURGH, PENNSYLVANIA, A CORPORATION OF ARIZONA.

GAS-CONDENSER.

1,071,648.

Specification of Letters Patent. Patented Aug. 26, 1913.

Application filed September 7, 1912. Serial No. 719,048.

To all whom it may concern:

Be it known that I, COMMODORE R. MILLER, a citizen of the United States, and residing in the borough of Woodlawn, in the county 5 of Beaver and State of Pennsylvania, have invented or discovered new and useful Improvements in Gas-Condensers, of which the following is a specification.

My invention consists in a new and improved condenser for gas.

The gas passes from the producer in a highly heated and expanded state, holding in suspension impurities or uncombined substances such as coal-tar, water-vapor, etc.

15 To fit the gas for use it is necessary to condense it and remove the impurities.

My condenser provides a tortuous gas-passage whose outer surface is air and water cooled and over which are caused to flow

20 continuous currents of cold water. Means are also provided for precipitating and drawing off the impurities.

My apparatus is inexpensive of construction and operation, occupying but little 25 space and effectively condensing and purifying the gas treated therein.

Many novel features of structure and arrangement of parts will appear from the following description.

30 In the accompanying drawings, Figure 1 is a side elevation of my condenser, the stand-pipes and base being shown in vertical section for the sake of clearness, and Fig. 2 is a plan view of the same, the stand-pipes 35 and gas-pipes being shown in horizontal section.

The following is a detailed description of the drawings:

A is an inclosed metal base or box provided along one side with tightly fitting 40 cleaning doors 1—1.

2 is a valved discharge pipe leading from the base A intermediate of its height and emptying into a water-seal 3. The base A is charged with water up to the level of pipe 2 and the valve in pipe 2 is normally open.

45 The top of base A is provided with a continuous vertical edge-flange 4, forming an open reservoir from which leads an overflow discharge pipe 5. The top of base A is also provided with a longitudinal row of circular ports, such as 6, 6^a, 6^b, 6^c, 6^d and 6^e. Between the ports 6^a and 6^b in the interior of base A is a depending baffle 7 whose lower

extremity is below the level of the water in 55 base A. A similar baffle, 7^a is located between the ports 6^c and 6^d.

B is a gas-pipe leading from the producer or other source of supply, not shown, and communicating with the port 6.

60 C is a substantially inverted U-shaped gas-pipe mounted on base A and having its legs communicating with the ports 6^a and 6^b. A similar pipe D connects ports 6^c and 6^d.

E is a pipe communicating with port 6^e 65 and connected with the gasometer or pipeline, not shown.

Gaskets 8—8 are interposed between the flanged bases of pipes B, C, D and E and the top of base A to obtain gas-tight joints. 70 The gas-pipes C and D are provided with capped hand-holes 9—9 for cleaning purposes.

F—F are vertical stand-pipes of greater 75 diameter than gas-pipes C, D and E and concentric therewith, the bases of said stand-pipes being mounted on and secured by water-tight joints to the base-flanges of said gas-pipes. The tops of pipes F—F are open 80 and their bases are connected to a water supply pipe G by branch pipes 10—10.

The operation of my invention is as follows: The gas entering through pipe B is deflected up into pipe C by baffle 7, passing 85 through said pipe C into base A in the rear of baffle 7. It is thence deflected by baffle 7^a into pipe D and passing through said pipe D enters the base A in the rear of baffle 7^a and escapes from the condenser through the pipe E. The water admitted to stand-pipes 90 F—F through pipes 10—10, fills said stand-pipes surrounding the vertical portions of pipes C, D and E with a constantly renewed supply of cold water. As the water flows over the tops of pipes F—F and runs down 95 the exterior surfaces thereof in a sheet, it becomes aerated and recooled and falls into the reservoir formed by the flange 4 chilling the base A and the excess escaping by pipe 5. The supply of water through pipes 100 10—10 is constant while the condenser is in use so that there is a continuous flow of cold water over the gas conductors. The result of the exposure of the gas to this cooling effect and its tortuous course through the 105 cooler is its condensation and the precipitation of the impurities, which latter are deposited in the water contained in the base A

and float off through the pipe 2, the escape of gas being prevented by water-seal 3. The base A may be cleaned, when required, through the doors 1—1.

5 What I desire to claim is:—

1. In a gas-condenser, a box formed with a bottom, sides and top, a continuous vertical edge flange projecting upward from the box-cover and forming an open-topped reservoir directly above said box-top, a discharge-pipe leading from said reservoir, 10 baffles disposed in said box, U-shaped pipes communicating with the interior of said box through said box-top, open-topped stand-pipes surrounding the vertical portions of 15 said U-shaped pipes, and means for supplying a cooling liquid, under pressure, to the base of said stand-pipes, causing the liquid to flow down over the exterior wall thereof, the cold water 20 sinking to the bottom of said reservoir and the warm water in said reservoir rising to the top and escaping through said discharge-pipe; whereby the said reservoir and, consequently, the interior of said box are maintained constantly chilled.
- 25 2. In a gas-condenser, a box formed with

a bottom, sides and top, a continuous vertical edge flange projecting upward from the box-cover and forming an open-topped reservoir directly above said box-top, a discharge-pipe leading from said reservoir, 30 baffles disposed in said box, U-shaped pipes communicating with the interior of said box through said box-top, open-topped stand-pipes surrounding the vertical portions of 35 said U-shaped pipes, and means for supplying a cooling liquid, under pressure, to the base of said stand-pipes, causing the liquid to flow down over the exterior wall thereof, the cold water 40 sinking to the bottom of said reservoir and the warm water in said reservoir rising to the top and escaping through said discharge-pipe; whereby the said reservoir, and, consequently, the interior of said box are maintained constantly chilled.

45 Signed at Pittsburgh, Penna., this 10th day of June, 1912.

COMMODORE R. MILLER.
